ELECTRIC MOTOR CONTROLLER

John M. Newman, Wauwatosa, Wis., assignor to
Cutler-Hammer, Inc., Milwaukee, Wis., a cor-
poration of Delaware

Application July 16, 1942, Serial No. 451,152

9 Claims. (Cl. 172—152)

This invention relates to improvements in controllers for motors in crane hoist and similar service.

In Patent No. 2,288,133, issued June 30, 1942, there is disclosed a controller for crane hoists, and the present invention while not limited thereto is especially applicable to such type of controller.

The controller of the aforementioned patent provides for operating a direct current motor as a series motor for hoisting and as a shunt motor for lowering and provides for dynamic braking of the motor under overhauling load conditions. Also it provides for high speed lowering at substantially the same speed whether the load is 15 heavy and overhauling or whether the hook is empty. In most instances it is desirable to maintain power connections for the motor throughout lowering and said patented controller is designed to maintain such connections.

On the other hand, it has been found desirable in certain instances, as where the system employs a Diesel engine or the like as a prime mover, to prevent the motor when driven by its load from pumping back current to the line, and the present invention has among its objects to provide a controller having substantially all the advantages of the controller of said patent but which will afford protection against pumping back of current by the motor.

Another object is to effect the desired control with but slight modification of said patented control.

Another object is to utilize for controlling disconnection from the line in lowering a relay serving to control for uniform high speed lowering under the different load conditions hereinbefore mentioned.

Other objects and advantages of the invention will hereinafter appear.

The present invention because of ease of embodiment in the aforementioned earlier controller has been so illustrated in the accompanying drawing which will now be described, it being understood that the invention is susceptible of 45 embodiment in other forms without departing from the scope of the appended claims.

In the drawing,

Figure 1 is a diagrammatic view which for simplicity of illustration omits numerous details 50 and control circuits now known to the art, and

Fig. 2 is a chart showing the sequence in which the switches or contactors shown in Fig. 1 are to be operated.

Referring to Fig. 1 of the drawing it shows a 55

motor M^1 having an armature A and a field winding F to be connected to lines L^1 , L^2 in series relation for hoisting and in shunt relation for lowering. These and other connections for the motor are made by switches which in type and number are the same as in the controller of the patent aforementioned, and as will be understood these switches are to be assumed to be operated by electroresponsive windings although in most instances the switches are here shown without windings for simplicity of illustration. In most instances the control of these switches is the same as in the controller of the patent aforementioned and in the drawing hereof such common circuits as well as the master switch contacts have for simplicity of illustration been omitted except where illustration has been made to clarify the modification here involved.

Switches M and H provide for connection of 20 the motor armature and field winding in series to lines L^1 and L^2 through resistors R^2 , R^3 , R^4 , R^5 and R^6 in series for hoisting, resistor R^1 being shunted throughout hoisting by switch 1A which is biased to closed position and switch 2DB being open instead of closed as shown. Resistors R^2 , R^3 and R^4 are adapted to be shunted progressively by switches 2A, 3A and 4A, respectively, these switches closing sequentially as shown by the chart Fig. 2 under the control of contacts 25 30 (not shown) of master switch MS and certain of said switches preferably having a definite time element incident to closure. Thereafter as indicated by said chart, switches 5A and 6A may be closed to shunt resistors R^5 and R^6 preferably subject to control to render their closure sequential and each subject to a definite time element. Thus provision is made for acceleration and speed control in hoisting in accordance with earlier practice, the indicated closure of switch 40 45 50 55 60 65 70 75 80 85 90 95 100 105 110 115 120 125 brake coil B to and through resistors R⁴, R³ and R² and thence through switch 1A and switch M to line L². As indicated by the chart, Fig. 2, switches 2A, 3A, 4A, 5A and 6A are closed in the first lowering position and thus if switch 1A remains closed the motor circuits are without resistance other than the resistor R⁷ common to the armature and field circuits and the fixed resistance R⁸ in the armature branch in parallel with the winding of the relay VR. This is in accordance with earlier practice, as is also opening of switches 4A, 5A and 6A in the second lowering position and opening of switch 3A in the third lowering position, all as indicated by the chart Fig. 2, first to include in the armature circuit resistors R⁵ and R⁶ and in the field circuit resistor R⁴, and then to include in the field circuit resistor R³. Meanwhile switch 1A remains closed for its operating winding is controlled by normally disengaged contacts 21 of the master switch MS, which contacts are not engaged until the master switch is moved to its fifth lowering position. As will be understood, the positions of the master switch which effect engagement of its contacts disengaged in off position are indicated by circles and thus as there is but one circle in line with contacts 21 it will be understood that said contacts shown as disengaged will remain in that relation except in the fifth lowering position later to be discussed.

As in the controller of the patent aforementioned and as indicated by the chart Fig. 2, the switch 2DB closes only in the off position of the master switch. When closed the switch 2DB completes a dynamic braking loop extending from the left hand terminal of the motor armature A to and through switches 5A and 6A to and through the winding of relay VR and parallel resistance R⁸ and thence to and through the winding O of relay 1CR and the contacts of switch 2DB to the right hand terminal of motor field winding F. This connects the motor armature and field winding in series for dynamic braking with the brake coil B excluded from circuit. As in the earlier controller and as shown by the chart Fig. 2 the switches 5A and 6A are now subject to control by the relay VR for graduation of dynamic braking as the motor comes to rest.

Now considering the provisions departing from the earlier control and again considering control for lowering, the relay 1CR has been given the dual function of controlling switch 1A and controlling switch 1KO. More specifically the relay 1CR which as in the earlier control is closed in all lowering positions pending overhauling of the motor opens whenever the motor overhauls, but if closed when the master switch MS is moved to final lowering position coacts therewith to energize switch 1A to insert in the field branch of the motor, resistor R¹, to afford a high speed for an empty hook substantially the same as the lowering speed under heavy overhauling load conditions. Also in the control here provided the switch 1KO is placed under the control of relay 1CR in the fourth and fifth lowering positions as indicated by the chart Fig. 2 whereby if when the motor tends to act as a generator with consequent response of relay 1CR the switch 1KO is caused to open to disconnect the motor from supply line L¹. This protects the system against undesired pumping back of current.

This dual functioning of the relay 1CR is provided for in the following manner. The winding O of relay 1CR is connected at all times in

series with the motor armature in lowering and is subject to current reversals when the motor acts as a generator, whereas the winding O¹ of said relay is subjected to only a unidirectional flow of current being connected across the line in series with the winding of under-voltage switch UV for energization continuously under normal conditions. Thus provision is made for the afore-described action of relay 1CR per se. The circuit for switch 1A controllable by relay 1CR extends from line L¹ through contacts 21 of the master switch MS but only when in its last lowering position by conductor 10 to and through the winding O of switch 1A by conductor 11 through auxiliary normally open contacts 12 of switch 6A by conductor 13 through the contacts of relay 1CR to line L². As shown there is a parallel circuit from conductor 13 through normally closed auxiliary contacts 14 of switch 2KO by conductor 15 to line L² but this parallel circuit is interrupted in the fourth and fifth lowering positions because of energization of the switch 2KO as shown by the chart Fig. 2, wherefore the switch 1A is under the control of the relay 1CR alone in the fifth lowering position. The circuit for switch 1KO controllable as aforesaid by the relay 1CR extends from line L¹ through the contacts 20 of the master switch MS in all lowering positions by conductor 16 through normally open auxiliary contacts 17 of switch M, by conductor 18 to and through the contacts of relay 1CR to line L². Alternatively circuit may be traced from conductor 18 by conductor 19 through the normally closed contacts 14 of the switch 2KO to line L² and thus as the switch 2KO is not energized except in the fourth and fifth lowering positions its auxiliary contacts 14 render energization of the switch 1KO independent of relay 1CR in the first three lowering positions but subject to control by said relay in the fourth and fifth lowering positions.

While the provisions just described prevent the relay 1CR from deenergizing the switch 1KO to disconnect the motor from line L¹ except in the fourth and fifth lowering positions it may in some instances be desirable for power saving or for other reasons to have switch 1KO under the control of relay 1CR in all lowering positions. Where this is desired it is only necessary to omit the auxiliary contacts 14 of switch 2KO.

With the modified control thus far discussed the speed torque characteristics are not as good as in the earlier control aforementioned, but substantially like characteristics have been found obtainable by providing as shown an armature shunt including a resistor R⁹ to by-pass from the motor field part of the armature current under overhauling load conditions. While the resistor R⁹ is shown as having permanent connection in the power circuit it is to be understood that it might have control means to make and interrupt its connection as desired, and that its location in circuit is susceptible of change. However, its location as illustrated has been found advantageous especially in minimizing its effect in both lowering and hoisting positions other than those for which it is provided.

In practice it may be desirable where slow speed hoisting is desired to close the switch 1KO in the first and possibly other hoisting positions thereby to provide for the motor an armature shunt and the master switch shown provides for closure of switch 1KO in the first and second hoisting positions.

What I claim as new and desire to secure by Letters Patent is:

1. In control for hoist motors, the combination with means selectively to establish power connections for hoisting or power and dynamic braking connections for lowering and to afford speed control, of means to render substantially uniform under heavy and light loads a high lowering speed selectable by the first mentioned means and to effect through the medium of said first mentioned means interruption of lowering power connections at certain of the lowering speeds when the load is overhauling.

2. In control for hoist motors, the combination with means selectively to establish power connections for hoisting or power and dynamic braking connections for lowering and to afford speed control, of means to render substantially uniform under heavy and light loads a high lowering speed selectable by the first mentioned means and to effect through the medium of said first mentioned means interruption of lowering power connections at certain of the lowering speeds when the load is overhauling, the second mentioned means comprising a relay which is subject to control by dynamic braking current and which renders said second mentioned means automatic in performing both aforementioned functions thereof.

3. In control for hoist motors, the combination with means selectively to establish power connections for hoisting or power and dynamic braking connections for lowering and to afford speed control, of means to render substantially uniform under heavy and light loads a high lowering speed selectable by the first mentioned means and to effect through the medium of said first mentioned means interruption of lowering power connections at certain of the lowering speeds when the load is overhauling, the second mentioned means having for rendering the same automatic in performing both aforementioned functions thereof a relay with control windings connected in circuit in lowering to act differentially or cumulatively according to the weight of the load.

4. In control for hoist motors, the combination with means selectively to establish power connections for hoisting or power and dynamic braking connections for lowering, said means affording any one of a number of speeds in hoisting or lowering and having an electro-responsive switch through which it tends at all lowering speeds to maintain said lowering power connections, of a relay to control said switch for action thereof to interrupt power connections at certain of the lowering speeds when the load is overhauling, said relay having a plurality of control windings one of which is subjected to a unidirectional flow of current regardless of load conditions and another of which is traversed by current changing in direction of flow according to whether the load is light or overhauling.

5. In control for hoist motors, the combination with means selectively to establish power connections for hoisting or power and dynamic braking connections for lowering, said means affording any one of a number of speeds in hoisting or lowering and having an electro-responsive switch through which it tends at all lowering speeds to maintain said lowering power connections, of a relay to control said switch for action thereof to interrupt power connections at

certain of the lowering speeds when the load is overhauling, said relay having a plurality of control windings one of which is subjected to a unidirectional flow of current regardless of load conditions and another of which is traversed by current changing in direction of flow according to whether the load is light or overhauling, and means controlled by said relay and the first mentioned means jointly to afford high speed lowering at substantially the same rate whether the load is light or overhauling.

6. In combination a series hoist motor, means selectively to establish power connections for said motor for hoisting, with the armature and field winding of the motor in series, or power and dynamic braking connections for said motor for lowering, with the motor field shunting the armature, means to effect through the medium of the first mentioned means during lowering at certain of the lowering speeds, interruption of power connections when the load is overhauling and a circuit to by-pass from the motor field winding some of the armature current for improved speed torque characteristics.

7. In control for hoist motors, the combination with means selectively to establish power connections for hoisting or power connections for lowering, said means including a master switch having different positions for selection of speeds in both hoisting and lowering and said means tending to maintain power connections throughout lowering regardless of the lowering position occupied by said master switch, and means effective when said master switch is in certain of its lowering positions to cause the first mentioned means to interrupt power connections under overhauling load conditions, but ineffective in other of the lowering positions of said master switch.

8. In a hoist system having as a prime mover a Diesel engine and having a hoist motor which under overhauling loads tends to pump back current with undesirable effects on such prime mover, the combination with motor controlling means which establish power connections for lowering and which afford a plurality of lowering speeds and tend to maintain power connections regardless of overhauling load conditions, of means effective under overhauling load conditions at least at certain of the lowering speeds to cause the first mentioned means to interrupt power connections, the first mentioned means including means which at certain of the lowering speeds renders the second mentioned means ineffective to function as stated.

9. In a hoist system having as a prime mover a Diesel engine and having a hoist motor which under overhauling loads tends to pump back current with undesirable effects on such prime mover, the combination with motor controlling means which establish power connections for lowering and which afford a plurality of lowering speeds and tend to maintain power connections regardless of overhauling load conditions, of means effective under overhauling load conditions at least at certain of the lowering speeds to cause the first mentioned means to interrupt power connections, and means which together with the second mentioned means provides means affording high speed lowering at substantially the same rate whether the load is light or overhauling.

JOHN M. NEWMAN.
